(54) **BEDSTEADS**

(76) Inventor: **Henry Reisinger**

Henry Reisinger of York, Pennsylvania
Letters Patent.

The Schedule referred to in these Letters Patent, and making part of the same containing a description in the words of the said Henry Reisinger himself of his improvement in the Bedstead.

To all to whom these presents shall come, Be it known that I Henry Reisinger of York in the County of York and State of Pennsylvania have invented a new and useful improvement in the art of making Bedsteads, and that the following is a full and exact description of the construction and operation of the said improvement, as invented or improved by me.

This Bedstead differs from the common Bedstead in general, The Bedstead to be of the ordinary length and Breadth, say 6 feet long, and 4 feet wide, between the posts. From the head post to the centre of the upper shaft is 2 feet 7 inches, the shaft to be made of hard wood two inches square with, gadroons on each end, which are to be one and a half or two inches long to extend or run into the center of siderails.

There are two cross pieces of hard wood stowed on the shaft extending from the head post to the semicircular rule joint, this which there is to be a pair of hard wood or iron put near the siderails. The length from the centre of the shaft to the end of the rule joint to be 23 inches, from the foot post to the other end of the rule joint is, twenty two inches.

The Bedstead to be made sufficiently high (say two feet two inches to the top of the rail, with casters or rollers underneath) to admit that part from the foot post to the rule joint to fall and rise easily as this Bedstead can be converted into a Bed or seat at pleasure.

There are four upright square posts, two of which are two inches from the rule joint to be of the same length, as

the other parts from the mid-tower to be made wide and tenoned into the lower part of the side rail; the other two are each to be twenty one inches from the tailing ones fastened into the lower part of the side rail in the same way, having croft pieces framed in said posts nine inches from the floor to to the top of said croft pieces. There is to be a small iron or wooden shaft round, or square parallel to the upper shaft which is to work on the above described cross piece, with a box or covering screwed on the yoke arm to keep it to its place, with one catch wheel on each end of said shaft and one truck which can be moved to either side of the bedstead. There is also a connecting rod, 4 feet 6 inches long of hard wood to work and roll on the shaft fastened to the lower side of the foot rail, with a piece screwed on the foot rail with a pin of wood or iron to let the rod work easy.

The rod to extend across the shaft three or four inches. There are three leather straps to be fastened with rivets, the middle leather to be precisely in the middle or centre of the shaft. The other end of said middle leather to be fastened to the rod. The other two to be fastened to the end of the croft pieces above described as near the side rails as said croft pieces are. The foot posts to consist of two posts to be made, or hung with hinges and fasten with small hooks and staples in order to let down that part of the bedstead which falls & also fastened with hooks on the inside of the posts to keep them secure in firm when the foot posts are on the floor. There may be a small pinion instead of the shaft to work on one, covered to the tail sufficiently long to let the falling part down with a croft piece of wood with a wire spring between the piece and the rail. The whole may be covered with strips of boards from two to six inches broad which will not bellow than wood. One of the strips to be stand or fastened on the rail.

joint and rounded off to suit the joint. The advantages of this bedstead are as follows viz. First it raises the bedding or bottom and lets the head part stand firm

2nd It can be placed in any corner of the room and occupies no more space than the common bedstead

3rd You can let the foot part down and raise the head part so as to form a seat or bench
